OIL DISTRIBUTING AND APPORTIONING DEVICE

Gustav Nemetz, Vienna, Austria, assignor to the
firm Alex. Friedmann, Vienna, AustriaApplication October 15, 1937, Serial No. 169,337
In Austria October 21, 1936

7 Claims. (Cl. 184—7)

This invention relates to central lubricating devices, and more particularly to an oil distributing and apportioning device which is inserted between a feeding device, such as an oil pump, and the individual places to be lubricated, and has for its object to supply these places, one after the other, with predetermined amounts of oil.

It has been already proposed to provide oil distributing devices of the class referred to above, wherein at a given moment one of two pistons is moved to feed a certain quantity of oil and the other piston is in its end position and serves to control the oil flow like a slide valve. To secure a satisfactory operation, the last named piston must be prevented from accidentally leaving its end position during the feeding stroke of the other piston. This is complicated by a special locking member which engages, and positively maintains one piston in its controlling or end position during the whole stroke of the other piston. Such an arrangement is relatively expensive and complicated and the locking member which is not accessible from outside is subject to the danger that it may be bound accidentally, thus disturbing the operation of the whole apparatus.

The main object of the present invention is to provide apparatus of the class referred to above, which avoids the enumerated inconveniences.

30 A further object of the invention is to provide oil distributing apparatus wherein the locking member is dispensed with and the locking means for maintaining one piston in its end position is formed by the other piston.

35 A still further object of the invention is to form the locking means of the pistons so that contact between both pistons during the operation takes place along sufficiently large surfaces in order to avoid a mutual binding of both pistons due to their relative engagement.

40 Another object of the invention is to improve the mechanism for measuring the quantity of oil delivered by the distributing apparatus, this mechanism forming part of the apparatus. 45 There are already known such mechanisms which indicate the number of feeding strokes of the pistons and include a driving member which passes from the interior of the casing of the distributing apparatus through a stuffing box or the like outwardly and act upon an indicating device consisting of a plurality of dials and arranged outside the casing. In such an arrangement the passing of said driving member 50 from the interior of the casing set under pres-

sure, outwardly results in certain inconveniences which are likewise removed by the invention.

Further objects and advantages of the present invention will result from the following description. 5

In the accompanying drawings some embodiments of the invention are illustrated by way of example.

Fig. 1 is a sectional view according to line I—I of Fig. 2. 10

Fig. 2 is a cross sectional view according to line II—II of Fig. 1.

Figs. 3 and 4 show a second embodiment. Fig. 3 is a section according to line III—III of Fig. 4 and 15

Fig. 4 is a section according to line IV—IV of Fig. 3.

Figs. 5 and 6 show a third embodiment. Fig. 5 is a section according to line V—V of Fig. 6 and 20

Fig. 6 is a section according to line VI—VI of Fig. 5.

Fig. 7 is a perspective view of a piston used in the device according to Figs. 5 and 6.

Figs. 8 to 15 show diagrammatically different positions of a detail of the device according to Figs. 5 and 6. 25

Figs. 16 to 18 show an indicating mechanism. Fig. 16 is a longitudinal section according to line XVI—XVI of Fig. 17. 30

Fig. 17 is a cross-section according to line XVII—XVII of Fig. 16, and

Fig. 18 is a plan view.

In the embodiment shown in Figs. 1 and 2, the casing 40 of the oil distributing apparatus is 35 provided with two cylindrical bores 2, 2_a arranged perpendicularly to each other in different planes, the spacing of which is such that the bores partly penetrate each other at their cross-point or centre of the device. The ends 40 of pistons 1 and 1_a fit snugly within the bores 2, 2_a, respectively and constitute movable walls of four chambers 100, 100_a, 100_b and 100_c formed near the ends of the bores 2, 2_a, respectively, and closed at their ends by plugs 26, 27 45 and 26_a, 27_a screwed into the casing. A channel 3 leading from the chamber 100 opens into the cylindrical wall of the bore 2_a, and in a similar manner the chamber 100_a is connected with the bore 2 through a channel 3_a, the chamber 50 100_b with the bore 2_a through a channel 3_b, and the chamber 100_c with the bore 2 through a channel 3_c. The piston 1 is provided with two annular recesses or necks 8 and 9, the edges of which serve to control the flow of the oil as it 55

will be described later on. The piston 2_a is provided with similar recesses 8_a and 9_a. The oil under pressure by a suitable pump or the like (not shown) is supplied to the device through a central opening 6. Channels 7, 7_a, 7_b, 7_c in the casing leading from the bores 2 and 2_a are connected by supply pipes fastened in the threaded holes 42, 42_a, 42_b, 42_c to the places to be lubricated so that four such places may be supplied with oil.

The pistons 1 and 1_a are moreover provided at about the middle of their length with two annular grooves 13, 14 and 13_a, 14_a respectively, which are formed and arranged so that when one piston assumes one of its end positions, the other piston is allowed to pass through one of these grooves of the first named piston. The grooves 13 and 14 communicate through a channel 15 passing through the piston 1, and the grooves 13_a and 14_a are likewise connected by means of a channel 15_a passing through the piston 1_a. As shown in Fig. 1, the recesses 8 and 9 of the piston 1 serve as a means to control the flow of lubricant through the channels 3_a and 3_c, whereas the recesses 8_a and 9_a of the piston 1_a serve as a means to control the flow of lubricant through the channels 3 and 3_b. Moreover, the recesses 8 and 9 of the piston 1 serve as a controlling means to connect or disconnect the channels 3_a and 7_a, or 3_c and 7_c, respectively, whereas the recesses 8_a and 9_a of the piston 1_a serve as a controlling means to connect or disconnect the channels 3 and 7, or 3_b and 7_b, respectively.

35 The device operates as follows:

In the position shown in Figs. 1 and 2, the piston 1 assumes its lower end position, and the piston 1_a assumes its right-hand end position so that the groove 14_a is in alignment with the bore 2 which accommodates the piston 1 and allows the same to move upwards. The oil under pressure enters through the opening 6 into the groove 14_a of the piston 1_a and also into the groove 13 of the piston 1, from where it flows 45 through the channel 15 into the groove 14 of the piston 1 and further through the channel 3_c into the chamber 100, so that the piston 1_a is maintained in its right hand end position. At the same time, the chamber 100_a is connected 50 through the channel 3_a, the recess 8 and the discharge channel 7_a to the associated point of consumption so that a slight pressure exists in chamber 100_a. This pressure is defined by the resistance to flow exerted from the respective 55 point to be lubricated. In a similar manner, the chamber 100_b is connected through the channel 3_b, the recess 9_a and the discharge channel 7_b to its associated point of consumption.

The oil entering at 6 moreover flows at the 60 same time from the groove 14_a through the channel 15_a, the groove 13_a and the channel 3 into the chamber 100 so that the piston 1 is moved upward and oil is forced thereby through the channel 3_b, the recess 9_a and the channel 7_b to the respective point of consumption. During this 65 movement of the piston 1 its unrecessed portion situated between the grooves 13 and 14, passes through the groove 14_a of the piston 1_a, thus preventing the piston 1_a from leaving its end 70 position.

After the piston 1 has completed its upward stroke which is limited by the plug 27 the groove 14 is in alignment with the bore 2_a so that the piston 1_a is allowed to move to the left, and the 75 recess 8 no longer provides communication be-

tween the channel 3_a and the channel 7_a, whereas the recess 9 has connected the channel 3_c with the channel 7_c. Now, the piston 1_a is moved to the left under the influence of the pressure prevailing in the chamber 100_a whereby oil is forced from the chamber 100_c through the channel 3_c, the groove 9 and the channel 7_c to the respective point of consumption. In a similar manner, thereafter the piston 1 is moved downwards and finally the piston 1_a is moved to the right again. In this manner a cycle including four feeding strokes is effected and such cycles are repeated continuously, the individual places to be lubricated being supplied with oil.

It is to be noted that at a given moment one piston exerts a feeding movement, while the other piston is stationary and acts in its end position as a means to control the flow of the oil, and that this stationary piston is not allowed to leave its end position, before the other piston has completed its stroke, since the stationary piston is maintained in its end position by the moving piston.

Due to the form of the grooves 13, 14 and 13_a, 14_a, as shown in Figs. 1 and 2, the slidable contact between the surface of the moving piston and the surface of the groove of the other piston is limited to points only so that a considerable pressure per unit of area occurs between these surfaces and thus, under certain circumstances, an excessive wear of these surfaces, as well as a mutual binding or holding of both pistons may be caused, whereby the operation of the device would be disturbed. These inconveniences may be removed by forming the grooves of one piston serving for the accommodation or passage of the other piston, in such a manner that the slidable contact between both pistons takes place not merely at single points, but along sufficiently large surfaces which may be curved or flat. Such an arrangement will be now described.

In the modification shown in Figs. 3 and 4, the general arrangement of the pistons and the several channels in the casing 40 is substantially the same as in Figs. 1 and 2. Instead of the grooves 13, 14 and 13_a, 14_a, however, recesses 16 and 17 are provided in the piston 1, and recesses 16_a and 17_a in the piston 1_a. These recesses have a circular cross-section and are formed by a cylindrical surface, the axis of which is perpendicular to that of the piston in which the recesses are formed, and the radius of which is substantially equal to the radius of the other piston. In the present example the radii of both pistons are equal, but these radii might also be different. It is to be noted that the moving piston passes through one of these recesses of the other piston, the contact between both pistons taking place along the whole cylindrical surface of this recess.

Between two feeding strokes of the pistons there exists a moment or short period of time, in which both pistons are in their end positions. In this position one circular recess of one piston is opposite one circular recess of the other piston so that when one or both pistons are accidentally rotated about their axes, the recesses are displaced so that passing of one piston through the recess of the other piston is no longer possible. In order to avoid this inconvenience means are provided to prevent the pistons from rotation about their axes. For this purpose bolts 18 and 18_a screwed into the casing 40 engage with their inner ends into longitudinal grooves 19 and 19_a.

in the pistons 1 and 1_a, respectively. In this manner the correct relative angular position of the pistons is always maintained. The admission port 6 is connected with the interior of the casing 5 by means of four channels 50 arranged about the bolt 18_a. The operation of the apparatus shown in Figs. 3 and 4 is the same as that of Figs. 1 and 2.

In the modification shown in Figs. 5, 6 and 7, 10 a pair of recesses 20, 21 are formed in the piston 1 and a similar pair of recesses are formed in the piston 1_a. These recesses are likewise formed so that the contact between both pistons during their movement takes place along sufficiently 15 large surfaces. In this example, these recesses are formed by a plain surface 22 in the piston 1, and 22_a in the piston 1_a, these surfaces being parallel to the axis of the associated piston. From the centre of each of these surfaces projects 20 a square stud 23 and 23_a, respectively, to such an extent that, when the pistons are assembled in the casing 40, the top surface 38 of the stud 23 of the piston 1 bears against the plain surface 22_a of the piston 1_a, the top surface 38_a of the stud 25 23_a of the piston 1_a bears against the plain surface 22 of the piston 1. By this mutual engagement the correct relative angular position of the pistons is assured so that special means to prevent the same from rotation about their axis are 30 superfluous. The studs, moreover, serve to lock one piston in its end position during the whole stroke of the other piston, as it will be described later on.

In the present example the studs 23 and 23_a 35 have a square outline and the length of a side of such a square is equal to one half of the stroke of the pistons, provided that, as in the present case, the strokes of both pistons have the same length. The strokes of both pistons may have 40 also different lengths and the studs must be so dimensioned that the sum of the dimensions of both studs 23 and 23_a, measured in the direction of the axis of one piston must be equal to the stroke of this piston.

In operation, the studs 23 and 23_a move around 45 each other, a slidable contact taking place between them along their lateral surfaces. Furthermore, the top surface 38 of the stud 23 slides along the plain surface 22_a, and the top surface 38_a of the stud 23_a slides along the plain surface 22. By means of this double engagement 50 angular movements of the pistons relatively to one another are prevented and that piston which is in its end position is prevented from leaving this position, before the other piston has completed its stroke.

In Figs. 8 to 15 the subsequent relative positions of the studs 23 and 23_a in the course of one operating cycle of the apparatus are diagrammatically indicated. At first the piston 1 moves 55 from its low end position shown in Figs. 5 and 6, upward, the stud 23 thus moving likewise upward (Fig. 8) and preventing the stud 23_a and therefore also the piston 1_a which is in its right-hand end position, from moving to the left. The stud 23 moves past the stud 23_a (Fig. 9) and when it has reached the position shown in Fig. 10 60 the stud 23_a and therefore the piston 1_a is allowed to move to the left (Fig. 11). The further relative movement of the studs 23 and 23_a will 65 be easily seen from the Figs. 12 to 15 and therefore need not be described.

In order to insert or remove the pistons into or from the casing 40 which consists of a single 70 piece, at both ends of the plain surface 22 of

the piston 1 there are provided grooves 24 and 25 formed as cylindrical surfaces, and in a similar manner the piston 1_a is provided with grooves 24_a and 25_a. The grooves 24 and 25 of the piston 1 are adapted to accommodate the full cross-section of the piston 1_a, and vice versa. For removing one of the pistons, for instance the piston 1_a, not only one of the plugs 26_a and 27_a, but also one of the plugs 26 and 27 must be removed. The piston 1 is then moved towards 10 the opened end of the bore 2 so that one of the grooves 24 or 25 comes into alignment with the bore 2_a so that the piston 1_a may be removed.

The Figs. 16, 17 and 18 show a mechanism for indicating the number of strokes of the distributing device and thereby the quantity of the oil delivered by the distributing apparatus. This mechanism is driven by one of the pistons of the distributing device, in the present example by the piston 1. Near the chamber 100 the casing 40 has a lateral extension 41 enclosing a cylindrical hollow space 29 in which an aperture 34 forming a window is provided. Into the hollow space 29 a glass tube 30 is inserted which encloses a stroke-indicator 31 including a number of dials the digits of which are visible through the glass tube 30 and the window 34. This stroke-indicator may be of any desired known construction and need not be described since it does not form part of the invention. Thus 35 the stroke-indicator 31 is situated in a space which communicates with the chamber 100 and is therefore also set under pressure, so that the space in which the stroke indicator is situated is filled by oil. This space is closed by the screw 36 plugs 26, 35 and 37. On the driving shaft 39 of the stroke-indicator 31 is fixed a rocking arm 32 which engages with its bifurcated end 33 into 40 an annular groove 28 formed in the end of the piston 1 so that a driving connection is established between the moving parts of the distributing device and the stroke-indicator 31.

When the lubricant is very dark so as to considerably impair the visibility of the digits of the dials of the stroke-indicator 31 a partition 45 wall 36 may be arranged between the space receiving this indicator and the chamber 100 and this space may be filled with another suitable liquid, such as glycerine or the like, which is sufficiently transparent and is not easily mixed 50 with the oil. It is not necessary that the shaft 39 be guided by the partition wall 36 with a tight fit since the lubricating oil will not be mixed with the glycerine or the like due to the fact that in the chamber 100 and in the space receiving the stroke-indicator substantially the 55 same pressure will prevail.

It is to be seen that by arranging the stroke-indicator 31 in a space under pressure, the objectionable arrangement is avoided wherein a 60 moving member passes from the interior of the casing 40 through the wall of the same outward in an oil tight manner.

What I claim is:

1. An oil distributing and apportioning device 65 comprising, a casing having two cylindrical bores closed at their ends and extending transversely to each other in said casing in two different planes the distance between the planes being such that said bores partly penetrate each other at 70 their cross-point, two pistons slidably in said bores, the ends of said pistons constituting movable walls of four chambers at the ends of said bores, said casing having two pairs of channels therein, one pair of channels leading from the 75

cylindrical surface of one of said bores to said chambers of the other bore, the other pair of channels leading from the cylindrical surface of the other bore to the chambers of the first bore, 5 said casing having two additional pairs of channels, one pair of said additional channels leading from the cylindrical surface of one of said bores to two discharge openings, the other pair of said additional channels leading from the cylindrical 10 surface of the other bore to two further discharge openings, said pistons having recesses for controlling the flow of oil through said channels, and said pistons having grooves arranged adjacent points of the pistons which cross each other so 15 that one piston is allowed to pass through a groove of the other piston when the latter is in one of its end positions.

2. An oil distributing and apportioning device as set forth in claim 1, wherein two of said 20 grooves are provided in each piston so that one piston is allowed to pass through one of these grooves of the other piston when the latter is in one end position and through the other of these grooves of the other piston when the latter is in 25 the other end position.

3. An oil distributing and apportioning device comprising, a casing having two cylindrical bores closed at their ends and extending transversely to each other in said casing in two different planes 30 the distance between the planes being such that said bores partly penetrate each other at their cross-point, two pistons slidable in said bores, the ends of said pistons constituting movable walls of four chambers at the ends of said bores, said 35 casing having two pairs of channels therein, one pair of channels leading from the cylindrical surface of one of said bores to said chambers of the other bore, the other pair of channels leading from the cylindrical surface of the other bore 40 to the chambers of the first bore, said casing having two additional pairs of channels, one pair of said additional channels leading from the cylindrical surface of one of said bores to two discharge openings, the other pair of said additional 45 channels leading from the cylindrical surface of the other bore to two further discharge openings, said pistons having recesses for controlling the flow of oil through said channels, and each of said pistons having two transverse recesses arranged 50 at those points of said pistons which cross each other during their relative movement, each of said transverse recesses being formed as a cylindrical surface the axis of which is perpendicular to the axis of the piston in which the recess is formed, and the diameter of each transverse recess being substantially equal to the diameter of the other piston so that one piston is allowed to pass through one of the transverse recesses of the other piston when the latter is in one of its 55 end positions.

4. An oil distributing and apportioning device as set forth in claim 3, wherein means are provided to prevent said pistons from rotation about their axes.

5. An oil distributing and apportioning device comprising, a casing having two cylindrical bores closed at their ends extending transversely to each other in said casing in two different planes

the distance between the planes being such that said bores partly penetrate each other at their cross-points, two pistons slidable in said bores, the ends of said pistons constituting movable walls of four chambers at the ends of said bores, 5 said casing having two pairs of channels therein, one pair of channels leading from the cylindrical surface of one of said bores to said chambers of the other bore, the other pair of channels leading from the cylindrical surface of the other bore to the chambers of the first bore, said casing having two additional pairs of channels, one pair of said additional channels leading from the cylindrical surface of one of said bores to two discharge openings, the other pair of said 10 additional channels leading from the cylindrical surface of the other bore of two further discharge openings, said pistons having recesses for controlling the flow of oil through said channels, each piston having two transverse recesses arranged 20 at those points of the pistons which cross each other during their relative movement, each of said transverse recesses being formed by a plain surface, a projection on each of said surfaces, said surfaces and said projections being so formed that 25 one piston is allowed to pass through one recess of the other piston when the latter is in one of its end positions and during such movement an outer surface of the projection of one piston slides along the plain surface of the other piston and the 30 lateral surfaces of both projections slide past one another.

6. An oil distributing and apportioning device, as set forth in claim 5, wherein a groove is provided at both ends of said plain surfaces of both 35 pistons to accommodate the full cross-section of the other piston when being in alignment with the latter.

7. An oil distributing and apportioning device comprising, a casing having two cylindrical bores 40 closed at their ends and extending transversely to each other in said casing, a piston slidable in each of said bores, the ends of said pistons constituting movable walls of four chambers at the ends of said bores, said casing having two pairs 45 of channels therein, one pair of channels leading from the cylindrical surface of one of said bores to said chambers of the other bore, the other pair of channels leading from the cylindrical surface of the other bore to the chambers of the first bore, said casing having two additional pairs of channels, one pair of said additional channels leading from the cylindrical surface of one of said bores to two discharge openings, the other pair of said additional channels leading from the cylindrical surface of the other bore to two further 50 discharge openings, said pistons having recesses controlling the flow of oil through said channels in such a manner as to apportion by cyclical rotation limited quantities of oil from the source of pressure through said chambers to said four discharge openings, projections on each of said pistons at those points of said pistons which cross each other during their relative movement, one projection of the one piston preventing the other piston from leaving its end position while the first piston executes its stroke.

GUSTAV NEMETZ.
